UNITED STATES PATENT OFFICE.

ALEXANDER C. SCHUMAN, OF LOUISVILLE, KENTUCKY.

WATER-CLOSET.

1,333,638.

Specification of Letters Patent. Patented Mar. 16, 1920.

Application filed October 15, 1918, Serial No. 258,192. Renewed August 11, 1919. Serial No. 316,836.

To all whom it may concern:

Be it known that I, ALEXANDER C. SCHUMAN, a citizen of the United States, residing at Louisville, in the county of Jefferson 5 and State of Kentucky, have invented certain new and useful Improvements in Water-Closets, of which the following is a specification.

This invention relates to flushing apparatus for water closets which are located outside of dwellings, and its object is to provide a structure whereby all danger of freezing of the apparatus is eliminated, and clogging of the discharge pipe avoided.

15 The invention also has for its object to provide a flushing apparatus which renders the closet perfectly sanitary.

The objects stated are attained by means of a novel combination and arrangement of 20 parts to be hereinafter described and claimed, and in order that the same may be better understood, reference is had to the accompanying drawing forming a part of this specification.

25 In the drawing, Figure 1 is an elevation of the apparatus, partly in section, and Fig. 2 is a similar view of a fragment of the apparatus, with certain parts in another position from that shown in Fig. 1.

30 The preferred embodiment of the invention has been illustrated, but it will be understood that various changes and modification may be made without a departure from the spirit and scope of the invention as 35 claimed hereinafter.

The reference numeral 5 in the drawing denotes a closet bowl provided with a pivoted seat 6, and adapted to be flushed from a tank 7 obtaining a water supply through 40 a pipe 8 connected to a suitable source. The tank is provided with a float-controlled inlet valve 9 which is closed by a lever 10 carrying a float 11. When a predetermined water level in the tank is reached, the lever 45 10 presses the valve 9 closed. The water is discharged from the tank into the bowl 5 through an outlet pipe 12, an ordinary ball flushing valve 13 being also provided. This valve is connected to a lever 14 provided 50 with a depending actuating rod 15.

In the pipe 8 is interposed a three-way valve 16 having a drain outlet 17, and an actuating arm 17^a, to which latter a rod 18 is connected. This rod extends alongside 55 the bowl 5, and its upper end is in the path of an abutment 19 on the seat 6, so located

that when the seat is swung down, said abutment engages the rod and pushes the same downwardly to open the valve and turn on the water. When the seat is up, a spring 60 20, engaging an abutment 21 on the rod, elevates the latter, whereby the valve is operated to shut off the water, and at the same time communication is established between the pipe 8 and the drain outlet 17, as shown 65 in Fig. 1.

The bowl 5 opens at its bottom or outlet end into a second bowl 22, which latter, in turn, is arranged to discharge into a receiving chamber 23 having an outlet 24 provided with a sewer connection 25.

The outlet end of the bowl 5 is provided with a closure in the form of a pivoted flap valve 26 connected by a link 27 to the seat 6 in such a manner that said valve is opened 75 when the seat is swung down for use, as shown in Fig. 2. When the seat is up, the valve is closed, in which latter position it seats over the bowl outlet and forms an effective seal to prevent escape of sewer gas. 80

The outlet end of the second bowl 22 is provided with a closure 28, which latter is also in the form of a pivoted flap valve. This valve is designed to close the outlet of the bowl 22 when the seat 6 is down and the 85 closet is in use. As shown in Fig. 1, the valve 28 has a laterally extending arm 29 to which is connected a vertically extending rod 30 which projects from the chamber 23 and extends alongside the bowl 5 so as to locate its upper end in the path of an abutment 31 on the seat 6. A spring 32 is also connected to the arm 29 for opening the valve 28. When the seat 6 is lowered for use, the abutment 31 strikes the upper end 95 of the rod 30, and the latter, as it moves downwardly, closes the valve 28.

The rod 30 is flexible so that it may be tripped off the abutment 31, this being done by a bell-crank lever 33 having one of its 100 ends connected to the rod 15, and its other end located alongside the rod 30. Assuming the seat 6 to have been lowered, and the valve 28 to have been closed by the engagement of the abutment 31 with the rod 30, if 105 now the rod 15 is pulled downwardly to open the flushing valve 13, the bell-crank lever 33 forces the rod 30 sidewise clear of the abutment 31, whereupon the spring 32 opens the valve 28. The purpose of this 110 operation will be presently made clear.

The seat 6 is provided with a spring catch

34 for holding the same down, said catch engaging a keeper lug 35 on the bowl 5. When the catch is released, the seat is automatically raised by a spring 36 connected to its rear end as shown in Fig. 2.

The tank 7 also has an auxiliary outlet 37 connected to the flushing pipe 12, and provided with a float-controlled valve 38. When the tank 7 is empty, the float 39 of the valve 38 is down, and said valve is open. It will therefore be seen that a small supply of water flows into the bowl 5 while the tank is filling, and as the float 39 rises and closes the valve 38, this flow ceases.

15 From the inlet valve 9 extends a hook-shaped stem 40 engageable by the float lever 10 when the float 11 is down, this being for the purpose of opening the valve 9 to permit the pipe 8 to drain.

20 Fig. 1 shows the normal position of the parts. The bowl 5 is closed to the bowl 22 by the valve 26, and the valve 28 is open. Upon lowering the seat 6, the valve 26 swings open as shown in Fig. 2, and the valve 28 is closed as hereinbefore described. The valve 16 is also opened to admit water into the tank 7, and when a predetermined water level is reached, the valve 9 is permitted to close by the float lever 10. When 30 the water commences to flow into the tank, a small quantity escapes through the pipe 37 and flows through the pipe 12 into the bowl 5 and passes from the latter into the bowl 22, in which it collects above the valve 28, and as said valve is closed, the water prevents fecal matter from sticking thereon. The flow of water through the pipe 37 ceases when the valve 38 closes, and the tank then continues to fill until the valve 9 closes.

40 To flush the bowl 5, the rod 15 is pulled downwardly, which, through the lever 14, unseats the flushing valve 13. At the same time, the bell-crank lever 33 pries the rod 30 away from the abutment 31, whereupon 45 the spring 32 opens the valve 28, and as the valve 26 is already open, the contents of the bowls 5 and 22 can escape into the chamber 23 and pass into the sewer connection 25.

When the seat is raised, the abutment 19 50 leaves the stem 18, whereupon the spring 20 places the valve 16 in closed position, and establishes communication between the pipe 8 and the drain outlet 17, and as the valve 9 was opened by the engagement of the float lever 10 with the stem 40 when the tank emptied, any water remaining in the pipe 8 can escape, so that all danger of freezing is eliminated. The valve 16 will be located 55 below the surface of the ground so as to be 60 beyond the freezing line.

Before the seat 6 can be swung upward by the spring 36, it is necessary to disengage the catch 34 from the keeper 35. The flushing operation must be effected while the seat 65 is down, and hence the catch prevents the

seat from swinging up when the occupant leaves the same.

I claim:

1. In a closet, the combination of a pair of communicating receptacles each having an outlet and said receptacles being arranged one above the other, a pivoted seat for the upper receptacle, a normally shut closure for the upper receptacle outlet, a connection between the seat and the closure for opening the latter when the seat is lowered, a normally open closure for the lower receptacle outlet, means actuated by the seat for shutting the last-mentioned closure when the seat is lowered, and means for disconnecting said shutting means to allow the closure to open. 80

2. In a closet, the combination of a pair of communicating receptacles each having an outlet and said receptacles being arranged one above the other, a pivoted seat for the upper receptacle, a normally shut closure for the upper receptacle outlet, a connection between the seat and the closure for opening the latter when the seat is lowered, flushing means for the receptacles, controlling means for the flushing means, a normally open closure for the lower receptacle outlet, means actuated by the seat for shutting the last-mentioned closure when 90 the seat is lowered, and means actuated by the aforesaid controlling means for disconnecting the shutting means to allow the closure to open. 95

3. In a closet, the combination of a pair of communicating receptacles arranged one above the other and each having an outlet, a pivoted seat for the upper receptacle, a normally shut closure for the upper receptacle outlet, a connection between the seat and the closure for opening the latter when the seat is lowered, a normally open closure for the lower receptacle outlet, a flexible rod connected to said closure, means on the seat and engageable with the rod for shutting the closure when the seat is lowered, and means for tripping the rod off said means to allow the closure to open. 100

4. In a closet, the combination of a pair of communicating receptacles arranged one above the other and each having an outlet, a pivoted seat for the upper receptacle, a normally shut closure for the upper receptacle outlet, a connection between the seat and the closure for opening the latter when 115 the seat is lowered, flushing means for the receptacles, controlling means for the flushing means, a normally open closure for the lower receptacle outlet, a flexible rod connected to said closure, means on the seat and engageable with the rod for shutting the closure when the seat is lowered, and means actuated by the aforesaid controlling means for tripping the rod off last-mentioned 120 means to allow the closure to open. 125

5. In a closet, the combination of a pair of communicating receptacles arranged one above the other and each having an outlet, a pivoted seat for the upper receptacle, a connection, a shut-off valve in the supply connection and a float-controlled valve for the auxiliary outlet, said valve closing before the second-mentioned valve closes. 25
- 5 10 15 20
5. In a closet, the combination of a pair of communicating receptacles arranged one above the other and each having an outlet, a normally shut closure for the upper receptacle outlet, a connection between the seat and the closure for opening the latter when the seat is lowered, flushing means for the receptacles, controlling means for the flushing means, a normally open closure for the lower receptacle outlet, means actuated by the seat for shutting the last-mentioned closure when the seat is lowered, means actuated by the aforesaid controlling means for disconnecting the shutting means to allow the closure to open, and a latch for locking the seat in lowered position.
6. In a closet, the combination of a receptacle, a flushing tank having main and auxiliary outlets into the receptacle, a supply connection to the tank, a flushing valve for the main outlet, a float valve for the supply
7. In a closet, the combination of a pair of communicating receptacles arranged one above the other and each having an outlet, a closure for each outlet, the closure of the upper receptacle outlet being shut when the other closure is open, and vice versa, a flushing tank connected to the receptacles, said tank having main and auxiliary outlets, a supply connection to the tank, 30 a flushing valve for the main outlet, a float valve for the supply connection, a shut-off valve in the supply connection, and a float-controlled valve for the auxiliary outlet, said valve closing before the second- 35 40 mentioned valve closes.

In testimony whereof I affix my signature.

ALEXANDER C. SCHUMAN.
